UNITED STATES PATENT OFFICE.

CHARLES HERMAN, OF ALLEGHENY, PENNSYLVANIA, ASSIGNOR TO
HERMAN PNEUMATIC MACHINE COMPANY, OF ZELIENOPLE,
PENNSYLVANIA, A CORPORATION OF PENNSYLVANIA.

MOLDING-MACHINE.

No. 851,166.

Specification of Letters Patent.

Patented April 23, 1907.

Application filed June 22, 1905. Serial No. 266,480.

To all whom it may concern:

Be it known that I, CHARLES HERMAN, a resident of Allegheny, in the county of Allegheny and State of Pennsylvania, have invented a new and useful Improvement in Molding-Machines; and I do hereby declare the following to be a full, clear, and exact description thereof.

My invention relates to molding machines and has special reference to that class of sand molding machines shown in Letters Patent No. 706,751 granted to me on August 12, 1902.

The object of my invention is to provide a cheap, simple and effective device for lifting the flask from around the pattern resting upon the jarring device, after a mold has been formed in said flask, in an even, rapid and easy manner and without the employment of laborious and uncertain devices.

A further object of the invention is to cheapen, simplify and render more effective the jarring mechanism and thereby compact the sand around the pattern in the flask more rapidly and evenly.

To these ends my invention consists, generally stated, in the novel arrangement, construction and combination of parts, as hereinafter more specifically set forth and described and particularly pointed out in the claims. Therefore, to enable others skilled in the art to which my invention appertains to construct and use my improved molding machine, I will describe the same more fully, referring to the accompanying drawings, in which—

Figure 1 is a side elevation of my improved molding machine showing the parts in their normal position. Fig. 2 is an end view and partly in section of the same, showing the mold and flask raised from the pattern after the sand has been jarred and the mold formed. Fig. 2^a is a like view showing the parts in a normal position. Fig. 3 is a vertical section of the jarring devices. Fig. 4 is an enlarged vertical section of the valve-chest and looking at the face of the valve. Fig. 5 is a top plan view of the machine with the pattern-plate removed. Fig. 6 is a cross-section on the line 6—6 Fig. 4.

Like symbols of reference herein indicate like parts in each of the figures of the drawings.

As illustrated in said drawing 1 is the base plate upon which my improved molding machine is supported and upon which the usual jarring-block 1' is secured, while extending up from said base-plate and around said block is the cylindrical casing 2 which is provided with the enlarged upper end 2' and is secured to said plate by the bolts 3 passing through the flange 3' on said casing and taking into said base-plate. Within the casing 2 is the jarring post 4 which has the cross-head 5 fitting around and secured to the upper end of the same and on this head are a series of upwardly extending projections or lugs 5' which slide on the guides 5'' and support the pattern-plate 6' on which the pattern 6 is mounted, while said pattern-plate is provided with a series of lugs 6'' for supporting a stripping-plate 7 upon which is carried the flask 8 having lugs 8' extending out from the same for engaging with the dowel pins 7' and with the lugs 7'' of the stripping-plate.

The lower end of the jarring post 4 is adapted to contact with the jarring-block in the operation of jarring, as hereinafter described, and the raising and lowering of this post is accomplished by the jarring mechanism which is located in the casing 2 and comprises a cylinder 9 which extends around said post and is held in place and stationary by being suitably secured to the casing 2. The cylinder 9 is provided with the usual heads 9', and stuffing boxes 9'' thereon through which the post 4 is moved, and such post is provided with a piston 10 secured thereon for working within said cylinder, while from the upper head pipes 11 project upwardly to allow the air within the cylinder above the piston to escape in its upward stroke to prevent any cushioning action within said cylinder and at the same time permit the air to enter said cylinder in the downward stroke to assist the free movement of said piston, such pipes having elbows 11' at their upper ends in order to prevent any sand, dirt etc. entering said cylinder through said pipes. The cylinder 9 has the valve-chest 12 within which travels a slide valve 13 which is provided with the narrow supply port 13' within the same and the large exhaust chamber 13'' which are adapted to communicate with the supply and ex-

haust ports 14 in the cylinder wall leading through and into the lower end of the cylinder 9 and the auxiliary exhaust-port 14' in said cylinder wall, while the latter port 14' opens at its lower end into the casing 2. Connected to the slide-valve 13 is the valve-stem 15 which moves through the usual stuffing boxes 12' on each end of the valve-chest 12 and through a lug 5" on the cross-head 5 at the upper end of said stem, while the movement of the stem is limited by the nuts 15' on said stem. The valve-stem fits within a yoke 13^a on the valve 13 and is held in place by the shoulders 15" on said stem fitting against each side of said yoke, while bars 16 are placed on said valve and springs 16' are interposed around 16" on said bars and between said bars and the outer side of the valve-chest 12 to hold said valve in place 10 against the walls of the cylinder 9 and cover the ports 14, 14' therein. Leading from any suitable source of supply is the valve controlled supply pipe 17 which passes through the walls of the casing 2 and is screwed into the outer side wall of the valve-chest 12 for supplying the fluid pressure into said chest.

The lifting of the flask 8 after the compacting of the sand therein by the jarring mechanism above described so as to form the mold cavity 8" by the pattern 6 is an operation similar to that shown and described in the patent referred to and in Letters Patent No. 647,673 granted to Henry C. Herman, April 17, 1900 for a molding machine and consists of two lifting devices placed one on each side of the casing 2 having the shafts 18 provided with cross-pieces 19 at their upper ends, on which the horizontal extensions 20 are mounted, which are 15 removably secured to each end of said cross-pieces by the adjusting bolts 19' passing through holes 20' in the extensions and taking into the said cross-pieces. These horizontal extensions are provided with a 20 number of holes 20' or slots if desired therein to permit the adjustment of the same for different sizes of stripping-plates and flasks and they are also provided at their inner ends with an upwardly extending flange 20" 25 for engaging with the stripping plate to raise it and the flask when desired and as herein-after described.

The lifting-shafts 18 are connected to the cross-pieces 19 at their upper ends by means 30 of the sockets 20^a formed on said pieces and are held therein by means of the set-screws 20^b passing through said sockets and engaging with the said shafts. Below the cross-pieces 19 the shafts 18 pass through caps 21 35 and into cylinders 22 which are secured at their lower ends by the threaded connections 23' within sockets 23 formed on the base-plate 1. These shafts 18 have pistons 18' secured at the lower ends thereof and they 40 are also provided with a key 24 therein with

which a key-way 24' in the caps 21 engages in order to keep said shafts from turning. The caps 21 are secured by bolts 21' to the brackets 25 which extend out from the casing 2 and are secured thereto by bolts 25' 70 passing through flanges 25" on said brackets and taking into said casing. These brackets 25 in addition to supporting the caps 21 also have the upper ends of the cylinder 22 extending into the same where they are supported and secured by a threaded connection like that shown at 23' at the lower ends thereof.

The shafts 18 are adapted to be raised within the cylinders 22 by means of a fluid 80 pressure which enters the cylinders through the horizontal branch-pipes 26 which are connected at one end to an opening 26' formed in the sockets 20 at the lower ends of said cylinders and opening into the same and 85 their opposite ends are connected to a T-coupling 26" which is connected to the branch-pipes 27' extending at right angles to the branch-pipes 26 from which the vertical pipe 27 extends upwardly in front of the casing 2 and is supported by the bracket 28 extending from and secured to said casing 2. At the upper end of the vertical pipe 27 is the three-way controlling valve 29 to which is connected the supply pipe 29' which leads 90 from any suitable source of supply and such valve is provided with the operating handle 29". Between the caps 21 and brackets 25 are the vents 30^a which will allow the air within the cylinders 22 and above the piston 18' to escape on the upward movement of the shafts 18 in order to prevent any cushioning action within said cylinders and at the same time permit the air to enter said cylinders in the downward movement of said shaft in order to assist the free movement of said piston. 95

Extending around the upper end of the shafts 18 and secured thereto by the set screws 30' are the brackets 30 which extend 110 out therefrom and have pins 30" secured therein to which the links 31 are pivotally connected at one end while the opposite ends of said links are pivotally connected to the forked ends 31' of the arms 32'. The arms 115 32' are secured by a key connection 32" at their opposite ends to the ends of a rock-shaft 32 which extends across in the rear of the casing and acts to connect the two lifting devices together so that they shall move in 120 unison. This shaft 32 is mounted in the upper ends of the standards 33 and such standards are secured to the base-plate 1 by the bolts 33", while the shaft is held in position by means of collars 34 thereon fitting against 125 said bearings and secured to said shaft by the set-screws 34'.

Extending through holes 35' in a projecting portion 25" on the bracket 25 are the vertical rods 35 which are carried by the bracket 130

30 and pass through holes 35" in said brackets 30. These rods 35 are hung from the brackets 30 by the heads 36' at their upper ends and their lower ends are provided with 5 the spiral springs 36 which are held thereon by plates 37' fitting around said rods and against the adjusting nuts 37 engaging with the lower ends of said rods, such springs acting to engage with the projecting portions 10 25" on the brackets 25 when the shafts 18 are moved upwardly and thereby overcome any shocks or knocks taking place to the parts in such movement. The nuts 37' will also permit the raising and lowering of the springs 36 15 along the rods 35 in order to permit the adjustment of the said springs at different heights on said rods to vary the heights to which the lifting shafts 18 may be raised. Supporting rods 38 are secured at their 20 lower ends to the base-plate 1 by a threaded connection, which rods pass through holes in said projections 25" and have heads 38" at their upper ends for engaging with said projections.

25 The operation of my improved molding machine is as follows—The parts being in their normal position as shown in Fig. 1 with the pattern-plate 6' carrying the pattern 6 resting upon the lugs 5' on the cross-head 5, 30 the operator places the stripping-plate 7 over the pattern 6 and rests the same upon the lugs 6" of the pattern-plate, after which the flask is placed over the pattern and held in place by the dowel pins 7'. The flask 8 is 35 then filled with sand and the operator applies the operating fluid, preferably compressed air from any suitable storage tank, air pump or other source of supply through the supply pipe 17 into the valve chest 12 40 and passing around said chest will pass through the narrow port 13' in the slide-valve 13 and thence into the cylinder 9 through the port 14 and raise the piston 10 and post 4 to their highest position. As the 45 piston 10 and post 4 are thus raised the cross-head 5 connected to said post is also raised and by reason of the lugs 5' on said cross-head fitting under and against the pattern-plate 6' the said plate, pattern 6, stripping-plate 7 and flask 8 containing the sand are 50 all raised. As the cross-head 5 is thus raised the lug 5''' thereon will strike against the upper nut 15' on the valve-stem 15 and so raise the stem and slide-valve 13 so that the 55 supply port 13' will be covered and the exhaust chamber 13" will be placed in communication with the ports 14, 14' in the cylinder 9, thereby shutting off the supply of air to said cylinder from the pipe 17 and allowing 60 the air to exhaust through the ports 14, 14', which will permit the post 4, cross-head 5, pattern 6 and flask 8 to drop so that the lower end of the said post will strike against the jarring-block to compact the sand in the 65 said flask around the pattern. Just before

the time that the lower end of the post 4 has struck the jarring-block, the lug 5" on the cross-head 5 will have come in contact with the lower nut 15' on the valve stem 15 which will act to lower said stem and valve 13 thereon so that the narrow port 13' will again communicate with the supply port 14 and admit the air to the cylinder 9 through said ports from the pipe 17, as shown in Fig. 3 for another jarring operation. It will thus be seen 70 that these operations of raising and lowering the ports for the purpose of packing the sand are automatically performed and continuous so long as the operating fluid is allowed to flow from the supply-pipe 17.

After the sand within the flask 8 has been sufficiently jarred to thoroughly compact it around the pattern 6 therein by the operations above described and it is desired to raise said flask with its mold cavity from 85 around the pattern, the operator turns the handle 29" of the valve 29 in the proper direction which will allow the fluid pressure, and preferably compressed air from any suitable storage tank, air pump or other source 90 of supply to pass through the supply pipe 29' and through the vertical and branch pipes 27, 27' and 26 to the cylinders 22. As the air thus enters the cylinders 22 and under the pistons 18' it will act to raise said pistons and 95 shafts 18 thereon through the caps 21 and with them the cross-pieces 19 and brackets 30 and as these parts are also raised the projections or flanges 20" on the extensions 20 of said cross pieces will engage with the bottom 100 or the lugs 7" of the stripping-plate 7, thereby raising said plate and with it the flask 8 away from the pattern 6; while the pattern and pattern-plate 6' remain stationary on the cross-head 5, during this operation, as shown in Fig. 2. During this operation of raising the shafts 18 and flask 8 it will 105 be evident that both shafts will be controlled in their movement and will be raised simultaneously and in unison by reason of the 110 same being coupled or connected together as before described. After these parts are thus raised they are held from dropping by the pressure of the air within the cylinders 22, so that when the stripping-plate 7 and flask 8 115 have been thus raised above the top of the pattern 6, the operator lifts the flask off the stripping-plate and carries it to any suitable place, after which the lifting shafts 18 and their connecting parts can be lowered by 120 turning off the valve 29 which will allow the air within said cylinders to pass therefrom and return through the branch, vertical and supply-pipes and escape through the valve 29, thereby returning the lifting devices to 125 their normal positions, as shown in dotted lines in Fig. 2 and ready for another operation of lifting the flask.

It will be evident that other fluid than air—such as steam etc., can be used to operate 130

the motor of the jarring mechanism, as well as the lifting devices, and that various other modifications and changes in the construction and operation of the machine may be resorted to without departing from the spirit of the invention or sacrificing any of its advantages.

My machine is simple in its construction and operation, is very durable and by its use it has been found that the sand will be easily, rapidly and thoroughly packed around the pattern to form a perfect mold cavity. The stripping-plate and flask can be easily, quickly and uniformly raised from around the pattern and without the employment of any hard or manual labor. The lifting shafts for raising the flask will be controlled at all times by the toggle joint connected with the rock shaft, thereby overcoming any tilting or wabbling of the flask in such raising operation, and preventing any liability of injury to the mold cavity within such flask.

What I claim as my invention and desire to secure by Letters Patent is:

- 25 1. In a molding-machine, the combination of a base, a casing mounted thereon, a pattern-plate supported by the casing, a stripping-plate supported by and above said pattern-plate and carrying a flask, power cylinders mounted on opposite sides of said casing, lifting shafts operated by said cylinders for raising and lowering the stripping-plate, a rock-shaft mounted on said base and extending across the same and at some distance from the exterior of the casing, and connections between said rock-shaft and said lifting shafts whereby the said lifting shafts are

caused to move in unison; substantially as described.

2. In a molding-machine, the combination 40 of a base, a casing mounted thereon, a pattern-plate supported by the casing, a stripping-plate supported by and above said pattern-plate and carrying a flask, power cylinders mounted on opposite sides of said casing, 45 lifting shafts operated by said cylinders for raising and lowering the stripping-plate, a rock-shaft mounted on said base and exterior to said casing and extending across the base, and toggle-levers connected to said rock-shaft 50 and lifting shafts whereby the said lifting shafts are caused to move in unison, substantially as described.

3. In a molding-machine, the combination 55 of a base, a casing mounted thereon, a pattern-plate supported by the casing, a stripping-plate supported by and above said pattern-plate and carrying a flask, power cylinders mounted on opposite sides of said casing, lifting shafts operated by said cylinders for 60 raising and lowering the stripping-plate, brackets secured to said base, a rock-shaft mounted in said brackets exterior to said casing and extending across the base, and toggle-levers connected to said rock-shaft 65 and lifting shafts whereby the lifting shafts are caused to move in unison, substantially as described.

In testimony whereof, I the said CHARLES HERMAN have hereunto set my hand.

CHARLES HERMAN.

Witnesses:

WALTER FAMARISS,
J. N. COOKE.
